UNITED STATES PATENT OFFICE

165,788

ARMCHAIR

Jens Risom, New Canaan, Conn., assignor to Jens Risom Design Inc., New York, N. Y.

Application May 13, 1950, Serial No. 9,921

Term of patent 14 years

(Cl. D15—1)

To all whom it may concern:

Be it known that I, Jens Risom, a citizen of the United States, and a resident of New Canaan, in the county of Fairfield, State of Connecticut, have invented a new, original, and ornamental Design for an Armchair, of which the following is a specification, reference being had to the accompanying drawing, forming a part hereof.

In the drawing:

I claim:

The ornamental design for an armchair, substantially as shown.

JENS RISOM.
